UNITED STATES PATENT OFFICE.

JOHN H. BURKHOLDER, OF ASHLAND, OHIO, ASSIGNOR TO ELITE MANUFACTURING COMPANY, OF ASHLAND, OHIO.

JACK.

Application filed August 25, 1921. Serial No. 495,169.

To all whom it may concern:

Be it known that I, JOHN H. BURKHOLDER, a citizen of the United States, residing at Ashland, in the county of Ashland and State 5 of Ohio, have invented certain new and useful Improvements in a Jack, of which the following is a specification.

The present jack is made mainly of pressed sheet metal to provide a structure of relatively light weight, in which the parts are especially constructed to facilitate their assembly and connection, to promote ease of operation, and to give in union the strength and durability required to lift and support 15 the weight of an automobile or other heavy load.

In the drawings accompanying this application, Fig. 1 is a vertical section of a standard and a side elevation of the working parts 20 therein and Fig. 2 is a similar view with the operating lever raised and the left pawl disengaged from the rack bar as in lowering operations. Fig. 3 is a rear elevation of Fig. 2, and Fig. 4 is a side and sectional view of 25 a modified form of the invention. Fig. 5 is a horizontal section of the jack on line 5-5 of Fig. 7, and Fig. 6 is a horizontal section on line 6-6, of Fig. 8. Figs. 7 and 8 are side and sectional views corresponding to 30 Fig. 1, excepting that the pawl tripping device is set in an inactive position as in lifting operations. Figs. 9 to 20, inclusive, are perspective views of the separate pieces from which the jack is built.

The jack comprises a body 2 of sheet metal stamped or folded to provide a U-shaped standard in which two vertical guiding ribs 3-3 are pressed inwardly in the opposing side walls 4-4 at the top thereof 35 near the front wall 5 so that a ratchet lift bar 6 may be supported vertically in a slide- 40 able position therein with the sides of the bar engaged only with said ribs. However, bar 6 also has a cross pin 7 at its lower end 45 which assists in stabilizing the lift bar and in guiding it in its movement by engagement with the sides 4 of body 2, and the cross pin also prevents the lift bar from being withdrawn entirely from the standard, be- 50 cause the ends of the pin are adapted to engage the bottom ends of the ribs 3 and limit the upward movement of the lift bar. A short connecting cross piece 8 is inserted 55 within aligned slots 9 in the two side walls 4 to further confine the lift bar within stand-

ard 2 and this cross piece also acts as a brace between the sides 4. The upper end of standard 2 is cut away at an angle and the sides united together by rivets or bolts 10 which pass through loops or hooks 11 of a 60 separate bracing and closure strip of metal 12 placed between the side walls 4 flush with the upper inclined edges thereof. Other rivets or bolts 13 and 14 unite the sides 4 midlength and near the bottom end thereof, and a second bracing and closure plate 15 having hook-shaped ends is fastened by said bolts or rivets 13-14 between said sides, but the space between strip 12 and plate 15 is left open to permit a socket member 17 to 70 oscillate within limits therein. The bottom of standard 2 is closed by a flat base plate 18 which is united to the sides 4 by separate angle plates 19.

Oscillatory member 17 is made of two 75 stamped sheet-metal sections having perforated flanges 21 united face to face by rivets to provide a socket for an operating lever 22, and portions of these sections are offset laterally and terminated in rounded 80 end edges with a stop shoulder 23 adapted to strike the bottom edge of cross piece 8 to limit the down stroke of lever 22. Oscillatory member 17 is free to rock on a short shaft 24 extending through the sides of 85 standard 2, and a check pawl 25 is pivotally supported upon shaft 24 between the offset sides of member 17 which carry a cross pin 26 adapted to support a lift pawl 27. These 90 pawls co-act in raising and lowering lift bar 6, and a single coiled spring 28 is adapted to press both pawls into engagement with the ratchet teeth on lift bar 6 unless this movement is counteracted by a tripping device 29 having a more powerful 95 controlling spring 30. Weaker spring 28 has one extremity 31 extending downwardly into a shallow groove 32 in the rear side of lift pawl 27, while its opposite end 33 extends upwardly from a bent connecting extension 100 34 pivotally engaged with a perforated ear 35 on check pawl 25. The position of coiled spring 28 as carried by pawl 25 is such that the coiled portion is constantly engaged with the inner inclined side of closure plate 12 105 and that both extremities or arms of the spring are constantly under tension to press the pawls toward the ratchet lift bar regardless of the position of the oscillatory member. However, the pressure exerted by 110

this spring may be neutralized and overcome to permit the lift bar to move downwardly step by step, and this is accomplished by tripping member 29 which is pivotally supported upon bolt or rivet 13 immediately beneath oscillatory member 17. Thus, tripping member 29 is made of a strip of flat stock bent to provide a short side and a longer side with registering openings to receive bolt or rivet 13, and the flat cross connecting portion 36 at the inner end of member 29 is inclined in respect to the parallel sides so that the downwardly-extending fingers 37 and 38 on pawls 25 and 27, respectively, may ride thereon in tripping said pawls alternately upon the reverse strokes of lever 18 in lowering the lift bar 6 as delineated in Figs. 1 and 2. Stronger spring 30 acts to tilt the rear end of tripper member 29 downwardly and the front end upwardly as long as the bent connecting terminal 39 of said spring is at one side of pivot 13, but when tripping member 29 is placed at a reverse inclination as shown in Figs. 7 and 8 the pull of the spring is on the dead center or slightly on the opposite side of pivot 13 and the tripper member is retarded and held inactive. In this inactive position the pawls co-act to raise the lift bar 30 step by step when the lever is operated.

The longer side of tripper member 29 has a lateral lip 40 to permit the thumb or finger to press and tilt said member on its pivot, and spring 30 is connected at its lower end to the inwardly-bent end of plate 15 to facilitate the assembly of said parts. The upper end of plate 15 is also narrowed or cut away at each side to permit tripper member 29 to be pivoted on the bolt or rivet 13 and to permit the upper end of spring 30 to operate freely and to extend outside while the main portion of the spring is concealed and protected by the plate.

In Fig. 4 I show the same jack provided with a shorter rear closure plate 15', a slightly modified tripper member 29', and curved leaf spring 30' engaging and mounted upon said parts to control the action of the tripper member.

50 What I claim is:

1. In a jack, a U-shaped standard, a ratchet bar slidably mounted within said standard, an oscillatory lever mounted between the sides of said standard, a check pawl and a lift pawl associated with said lever and said ratchet bar, and a single coiled spring having its opposite extremities engaged with the respective pawls mounted in

bearing engagement with a part of said body to maintain a constant spring pressure on 60 said pawls.

2. A jack, comprising a U-shaped standard, a ratchet lift bar mounted within said standard, an oscillatory member and a check pawl and a lift pawl associated therewith and said lift bar adapted to raise and lower the bar, spring means adapted to throw said pawls into working engagement with said ratchet lift bar, depending fingers upon said pawls, a pivoted tripper member adapted to be turned into engagement with said fingers, and a closure plate and spring mounted between the side walls at the rear side of said standard, the spring having one end thereof connected with said tripping member. 75

3. A jack, comprising a hollow standard, a ratchet lift bar and pawl and lever mechanism mounted within said standard, a closure plate at the rear side of said standard beneath said lever and pawl mechanism, a 80 fastening bolt for said plate, a tripping member for said pawls pivotally mounted upon said bolt, and a spring connected with said tripping member and said plate.

4. A jack, comprising a standard having a 85 lift bar and an oscillatory member and pawls mounted therein, said pawls having depending fingers, a bolt extending transversely through said standard, a tripping member for said pawls having parallel sides pivotally engaged with said bolt and an inclined connecting portion at one end adapted to engage said fingers, and a spring mounted within said standard and connected with said tripping member. 95

5. A jack, comprising a sheet metal body folded into U-shape having a cross piece between its sides parallel with the front sides of said body, a cross shaft mounted upon the sides of said body opposite said cross piece, 100 an oscillatory member supported upon said cross shaft made in separate sections and united together to provide a socket having an operating lever, said sections being offset laterally and terminating in rounded end 105 edges with stop shoulders adapted to engage said cross piece, a lift bar mounted within said standard at the front side of said cross piece, and a lift pawl mounted upon said oscillatory member between said shaft and 110 said cross piece.

Signed at Ashland, county of Ashland, and State of Ohio, this 6th day of June, 1921.

JOHN H. BURKHOLDER.
